(57) **CLAIM**

The ornamental design for a magnetic pump wet end, as shown and described.

DESCRIPTION

FIG. 1 is a front view of a magnetic pump wet end showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective, front and left side view thereof; and,
FIG. 8 is a perspective, rear view thereof.

The broken lines shown in the drawing views are included for illustrative purposes only, and form no part of the claimed design.
